UNITED STATES PATENT OFFICE.

THOMAS I. DUFFY, OF CHICAGO, ILLINOIS, ASSIGNOR TO VOIGTMANN & COMPANY, OF CHICAGO, ILLINOIS, A COPARTNERSHIP.

AUTOMATIC WINDOW.

No. 845,767.

Specification of Letters Patent.

Patented March 5, 1907.

Application filed April 24, 1906. Serial No. 313,490.

To all whom it may concern:

Be it known that I, THOMAS I. DUFFY, a citizen of the United States, residing at Chicago, in the county of Cook and State of Illinois, have invented certain new and useful Improvements in Automatic Windows, of which the following is a specification.

This invention relates to improvements in automatic windows, and refers more specifically to improvements in fireproof windows of that type in which one or both of the sash are pivoted in such manner as to automatically swing shut by gravity when released.

Among the salient objects of the invention are to provide a stop mechanism which performs the combined function of rendering the sash weatherproof and at the same time automatically and positively locking the sash in closed position; to provide in such a mechanism an arrangement whereby the entire weight of the stop mechanism contributes to the certainty of locking movement thereof; to provide a construction in which the release of the sash to permit it to open is effected by withdrawing the stops and the opening of the sash serves to automatically hold the stops retracted; to provide a construction in which the locking mechanism (the stop mechanism) is wholly concealed within and protected by the sash and frame structure, thereby insuring that the sash will remain locked under any degree of exposure to heat short of that which actually disintegrates the frame; to provide a window of the character referred to characterized by its simplicity of construction and freedom from expensive and difficult-to-manufacture parts; to provide a construction in which the stops and co-operative mechanism therefor are all readily accessible and capable of being removed for inspection or repair after the window has been installed in a building; to provide a construction in which the retraction of the stops and unlocking of the movable sash is effected by applying a direct pull to a simple lever in such manner that the same force which unlocks the mechanism serves also to draw the window into open position; to provide a construction which has all of the characteristics of certainty in its automatic closing action which have pertained to prior art structures, and in general to provide a simple and improved mechanism of the character referred to.

To the above ends the invention consists in the matters hereinafter described, and more particularly pointed out in the appended claims.

The invention will be more readily understood from the following description, reference being had to the accompanying drawings, in which—

Figure 1 is an inside elevation of a window embodying the invention. Fig. 2 is a vertical sectional view taken on line 2 2 of Fig. 1 and looking in the direction of the arrows, but showing the sash open. Fig. 3 is a sectional view of a fragmentary part of the window structure, taken in a plane parallel with the plane of the window and extended through the stop-recess, certain parts being broken away to expose other parts in the rear thereof. Fig. 4 is a transverse vertical detail taken on line 4 4 of Fig. 1 and looking in the direction of the arrows. Fig. 5 is a horizontal sectional view taken on line 5 5 of Fig. 3 and looking downwardly.

Referring to the drawings, 1 designates as a whole the window-frame which, as usual in windows of fireproof structure, is made of sheet metal formed up to provide a hollow casing, the side members 2 2 of which are joined with the top and bottom members 3 and 4 by means of joints riveted or otherwise secured against separation by fire. In the preferred embodiment shown the side frame members 2 are formed in chief of a single piece shaped to provide an inner flat face or sash-frame seat 5, located about midway of the width of the casing over all, a groove or channel 6, located in said seat 5 and extending laterally outward, a rabbeted shoulder or retreating surface 7 extending along one margin of the seat 5, inner and outer faces 8 and 9, respectively, which define the outer planes of the frame, and returned portions 10 and 11, which are interlocked with tie-pieces 12, extending across the laterally outer sides of the frame. The tie-pieces 12 of the side frame members may desirably be provided with integral outstanding anchor-flanges 13, as seen clearly in Fig. 5.

The top frame member 3 is in cross-sectional form substantially similar to the side frame members, as seen clearly in Fig. 4. The bottom frame member 4 when designed as a part of a window having a stationary lower sash, as in the present instance, is of

suitable cross-sectional shape to form both the bottom frame member and the lower rail 14 of the bottom sash, as shown clearly in Fig. 2, the upstanding median rib which forms 5 the rail-body being provided with a channel 15 to receive the edge of the glazing 16.

The sash-frames (designated as a whole 17 and 18, respectively) may be of any suitable or preferred construction so far as their general features are concerned, except that the 10 movable sash is provided with stop-receiving grooves to register with those of the outer frame, as will now be described. As shown clearly in the drawings, the side stiles 19 and 15 the upper and lower rails 20 and 21, respectively, are each of hollow sheet-metal construction and provided in their inner faces with channels 22 and 23 for the reception of the glazing. The channel 23 in the top rail 20 has an open bottom, so that the edge of the glazing may be inserted therein far enough to enable the opposite edge to be brought into register with the channel of the bottom rail and then shifted downwardly into 25 engagement with the latter in a manner well understood by those familiar with this art, and for the same reason the vertical muntins 24 and 25 are of two-part construction, so that the outer members thereof may be applied after the glazing has been seated.

The side stiles 19 and the top rail 20 of the movable sash are each provided in their outer faces with stop-grooves, as 26 and 27, arranged to register with the corresponding 30 stop-grooves of the outer frame members.

One of the most important features of the present invention resides in the peculiar arrangement of the stop mechanism, whereby the stops not only serve the usual function of 35 closing and making weatherproof the joints between the sash and frame, but in addition thereto form an automatic locking mechanism which holds the sash closed in an extremely reliable manner. Describing this 40 mechanism and referring more particularly to Figs. 2 and 3, within each of the side members of the main frame are seated a pair of link-supporting brackets 28, each of which consists of a U-shaped sheet-metal member inserted from the inner face of the side frame 45 laterally outward and having its sides 29 in the same plane or in register with the sides of the stop-groove 6. (See Fig. 5.) The ends 30 of the U-shaped bracket are turned in opposite directions, so as to overlie the inner 50 face of the side frame member, and are secured in position by overlying integral clips 31, as shown clearly in Fig. 2. These brackets are of a depth somewhat greater than the 55 depth of the stop-groove 6, and between the side walls of each bracket near its laterally outer side is pivoted a link 32, which links are at their opposite ends pivoted to and carry the corresponding stop member 33. The 60 links are inclined obliquely upwardly from

their pivotal axes 34 to their points of attachment 35 with the stop and are parallel with each other, so that the bodily movement of the stop inwardly and outwardly is in parallelism with the side frame and side 70 rail of the sash. In the preferred construction shown the stops 33 are made of sheet metal and U-shaped in cross-section, the links being inserted between the two sides of each stop and the closed edge of the stop slightly rounded, 75 as shown clearly in the drawings. A generally similar stop 36 is arranged within the stop-groove 6' of the top frame member 3, and this stop is operatively connected with the upper ends of the side stops 33 by means of 80 sliding connections which permit lateral bodily movement of the side stops concurrently with the rising-and-falling movement of the upper stop. In the construction shown this is effected by providing transverse apertures 37 in the upper ends of the side stops, through which are extended the reduced ends 38 of the upper stop, the parts being free to slide upon each other. The lower edge of the upper stop is rounded both as a matter of 85 convenience of construction and for a purpose which will hereinafter appear.

It will be obvious that if the upper stop be lifted bodily it will, through its connections with the side stops, lift the latter, and thereby 90 cause them to move laterally outward and out of engagement with the grooves of the sash. In order to thus lift the upper stop, a lever 39 is pivotally mounted between its ends upon a bracket 40, mounted upon the 100 inner face of the top rail of the sash about mid-length of the rail, (see Fig. 2,) and one end of this lever extends through a suitable opening in the sash in position to intersect the stop-groove of the sash-rail and underlie 105 the stop. The opposite end of the lever projects outwardly, and an operating-chain 41 is connected therewith, this chain being provided with the usual fusible link 42. Upon pulling down the lever 39 the upper stop is 110 elevated and carried out of engagement with the top rail of the sash, and simultaneously the side stops are retracted and disengaged. A continued pull on the chain draws the upper edge of the sash inwardly into the tilted 115 position shown in Fig. 2, and in order that the lever may slide freely out of engagement with the lower edge of the upper stop it is rounded off, as to form an inclined surface 43. The inclined surface 43 of the lever also 120 depresses the latter and allows it to automatically pass under the edge of the stop in the closing movement of the sash. As soon as the sash begins to open the laterally outer faces thereof assume an angle to and extend 125 across the inner edges of the side stops 33, and obviously the latter cannot move inwardly until the sash is again brought into register with them—i. e., brought into closed position. The fact that the side stops are 130

thus held retracted obviously holds the upper stop uplifted so as to permit the sash to return to its closed position freely, whereupon the combined weight of the upper stop and both side stops acts to return the stops into their seats within the sash.

The movable sash is pivoted in such manner that it tends to swing into closed position by gravity. To this end pivot-plates 44 are secured to the respective side rails of the sash mid-length of the latter, each pivot-plate having an outstanding eye 45, within which is rigidly seated a pivot-stud 46. The pivot-studs extend laterally outward and enter pivot-apertures in corresponding bracket-straps 47, which are mounted upon the respective side frame members, as shown clearly in the drawings. In order to limit the tilting movement of the sash and prevent its being inadvertently reversed, a limiting-chain 48 is connected with the lower end of one of the bracket-straps 47 and with the corresponding end of the pivot-plate 44. This chain is detachably hooked to one of these members, so that in case it be desired to reverse the window for washing or other purposes it can readily be effected.

It will be understood from the foregoing description that a construction embodying my invention accomplishes the several objects hereinbefore set forth and is at the same time neat and finished in appearance and devoid of complicated mechanism and possible difficulty to construct. Windows of this character are largely used as protection against fire, and the simplicity of parts, positiveness of action of the locking mechanism, and absolute security with which the parts are locked in closed position is of much importance, it having been found that when fireproof windows are subjected to severe exposures the distortion and warping is so great that catches and the like cannot safely be relied upon to hold the window closed. Moreover such windows are frequently subjected to the action of streams of water from hose, and where the locking mechanism is exposed it is liable to be released by the impact of the water.

I claim as my invention—

1. In a window, the combination of a window-frame, a sash-frame pivotally mounted therein to oscillate on a transverse axis located between the ends of the sash, stops mounted upon the window-frame at each side of the sash and adapted to enter stop-grooves in the latter, upwardly and inwardly inclined parallel links pivotally supporting each of said stops upon the window-frame, and means for simultaneously lifting the stops to effect their withdrawal from the sash.

2. In a window, the combination of a window-frame, a sash-frame pivotally mounted therein to oscillate on a transverse axis lo-

cated between the ends of the sash, stops mounted upon the window-frame at each side of the sash and adapted to enter stop-grooves in the latter, upwardly and inwardly inclined parallel links pivotally supporting each of said stops upon the window-frame, and means for simultaneously lifting the stops to effect their withdrawal from the sash, said means comprising a horizontal bar extending between and operatively connected with the corresponding ends of the side stops and a lever operatively engaging said bar.

3. In a window, the combination of a window-frame provided in its inner vertical sides with stop-grooves, a sash-frame pivotally mounted therein and provided in its outer lateral sides with stop-grooves adapted to register with the corresponding grooves of the frame, parallel links at each side of the window pivotally mounted to oscillate in planes parallel with the stop-grooves of the frame and inclined upwardly and inwardly from their pivotal points of attachment to the frame, side stops supported by the sets of parallel links at each side, an upper transverse stop having sliding engagement with the upper end of each side stop and adapted to enter a stop-groove in the upper side of the sash-frame, and an actuating mechanism for positively lifting said upper stop and connected side stops.

4. In a window, the combination of a window-frame and a sash-frame pivotally mounted therein upon a transverse axis, said window-frame being provided in its inner perimeter surrounding the sash-frame at each side of the latter and across the upper end thereof with stop-grooves and the sash-frame being provided with corresponding stop-grooves adapted to register with those of the window-frame when the sash is in closed position, stops shiftably mounted in each of said several grooves of the window-frame, a pair of parallel links pivotally connected with each side stop-groove and also pivotally connected with the window-frame at points laterally remote from the stops, operative connections between the upper ends of the side stops and the corresponding ends of the upper transverse stop, said connections comprising guide-openings in the side stops and extensions of the upper stop sliding endwise within said guide-openings, and means for shifting said upper stop bodily into and out of engagement with the groove of the sash-frame.

5. In a sheet-metal window, the combination of a hollow window-frame having its inner perimeter at each side and across the upper end formed with a stop-groove, the sides whereof are parallel with the plane of the window, divided link-brackets seated in each side of the window-frame in register with the stop-grooves thereof, the sides of said brackets extending laterally outward from the in-

ner perimeter of the window beyond the lateral bottoms of the stop-grooves, parallel links pivotally mounted in the laterally outer portions of said brackets and extending obliquely upwardly and inwardly from their points of pivotal attachment, a side stop pivotally connected with the inner and upper ends of the links at each side of the window, an upper transverse stop movably mounted in the upper frame member of the window, sliding connections between the respective ends of said upper stop and the corresponding side stop, means for lifting said upper stop member bodily and thereby retracting the side stops, and means controlled by the pivoted sash for holding the several stops retracted so long as the sash is in open or partially-open position.

6. In a window, the combination of a window-frame, a sash-frame pivotally mounted therein to oscillate on a transverse axis located intermediate the height of the sash, said sash being provided with lateral stop-grooves and a stop-groove across its upper end, stops mounted upon the window at each side of the sash, and a third stop mounted upon the window-frame and extending across the upper end of the sash, means guiding said lateral stops to move in a bodily downward and inward direction whereby they are caused to enter the sash as they descend and retract from the sash as they ascend, and interconnections between the upper ends of the lateral stops and the corresponding ends of the upper stop whereby they are all retracted simultaneously.

7. In a sheet-metal window, the combination of a hollow window-frame having its inner perimeter at each side of the sash-opening formed with a stop-groove, the sides whereof are parallel with the plane of the window, a U-shaped bracket seated in the stop-groove at each side of the window having its terminal arms or ends turned oppositely outward and resting against the face of the window-frame, and means uniting said outturned ends rigidly with the frame.

8. In a window, the combination of a window-frame provided in its inner vertical sides with stop-grooves, a sash-frame provided with grooves adapted to register with corresponding grooves of the frame, and stops seated in said grooves, each stop being formed of sheet metal folded upon itself along a longitudinal line to form a double-thick stop, and stop-supports movably supporting said stops for lateral shifting movement, each support having its stop-engaging end inserted and secured between the two sides of the folded stop.

9. In a window, the combination of a window-frame provided in its inner vertical sides with stop-grooves, a sash-frame provided with grooves adapted to register with corresponding grooves of the frame, stops seated

in said grooves, each stop being formed of sheet metal folded upon itself along a longitudinal line to form a double-thick stop, and a pair of supporting-links pivotally connected with each stop and with the window-frame, said links having their stop-engaging ends inserted between the two sides of the folded stop, substantially as described.

10. In a window, the combination of a window-frame provided in its inner perimeter with stop-grooves, a sash-frame pivotally mounted therein provided in its outer margin with stop-grooves adapted to register with corresponding grooves of the frame, and stops operatively mounted in said members, each stop being formed of a strip of sheet metal folded upon itself along a longitudinally-extended line to form a rounded edge, and the stop-groove of that member receiving said rounded edge being correspondingly rounded at its bottom, substantially as described.

11. In a window, the combination of a window-frame provided in its inner vertical sides and across its top with stop-grooves, a sash-frame pivotally mounted therein and provided in its outer lateral margins and across its top with stop-grooves and adapted to register with corresponding grooves of the frame, stops operatively mounted in the respective stop-grooves of the window-frame; means guiding the lateral stops to move in a bodily downward and inward direction, and interconnections between the upper ends of the lateral stops and the ends of the upper stop comprising transverse socket-openings in the lateral stops, and socket-engaging extensions upon the upper stop engaging said sockets.

12. In a window, the combination of a window-frame provided in its inner vertical sides and across its top with stop-grooves, a sash-frame pivotally mounted therein and provided in its outer lateral margins and across its top with stop-grooves and adapted to register with corresponding grooves of the frame, stops operatively mounted in the respective stop-grooves of the window-frame, means guiding the lateral stops to move in a bodily downward and inward direction, interconnections between the upper ends of the lateral stops and the ends of the upper stop comprising transverse socket-openings in the lateral stops, socket-engaging extensions upon the upper stop engaging said sockets, and means for operating said stops comprising a lever pivotally mounted between its ends upon the upper rail of the sash and extending within the sash and underlying the upper stop, the stop-engaging end of said lever being inclined to form a cam-like surface adapted to bodily pass into and out of engagement with the stop.

13. In a window, the combination of a window-frame, a sash-frame pivotally mounted therein to oscillate on a transverse axis located between the ends of the sash and pro-

vided with lateral stop-grooves, stops mounted upon the window-frame at each side of the sash, means guiding said stops to move bodily in an inclined downward and inward direction, means upon the sash-frame operating to hold said stops retracted against their tendency to descend while the sash is open, and a retaining device automatically releasable by heat, for holding said sash in open position.

14. In a window, the combination of a window-frame, a sash-frame bodily mounted therein to oscillate on a transverse axis lo-

cated intermediate the height of the sash, said sash-frame being provided across its top with a stop-groove and the window-frame also provided with a stop-groove adapted to register with that of the sash when the latter is in closed position, a stop mounted to rise and fall bodily within said grooves, and a leverage mechanism arranged to retract said stop and release the sash.
